BUS OR CAR WINDOW CONSTRUCTION

Siegfried E. Blessin, Short Hills, N. J., assignor
to Transportation Sash Co. Inc., Topton, Pa.,
a corporation of Pennsylvania

Application September 7, 1939, Serial No. 293,668

4 Claims.

(Cl. 189—73)

This invention relates to improvements in bus or car windows; and more particularly to simplify the construction and facilitate the operation of windows especially adapted for use on buses, or the like.

Buses are at present constructed of metal as far as possible with substantially rectangular openings for windows. The windows are accurately manufactured into substantially true rectangles; but it is difficult to construct and maintain the window opening a true rectangle in the metal wall of the bus. This is objectionable in that the window does not properly fit into the opening, and it is either too loose causing annoying rattling when the bus is in motion, or it is too tight, making it difficult to raise or lower the window.

It is, therefore, an object of this invention to construct and facilitate the operation of windows by providing a movable member against which the side edges of the window bear, the moving of the member being resisted by springs of a peculiar construction providing a uniform resisting force at all times. By means of this construction, rattling and binding of the window is prevented, as the window engages the member at all times with the same force regardless of the accuracy of the fit between the window opening and the window.

A further object is to provide a window construction for buses and the like, which prevents the entrance of water to moving parts of the window, and thus prevents binding of such parts by corrosion resulting from water.

Another object is the provision of a construction which greatly decreases the cost of manufacture of windows for cars or buses.

These and other advantageous objects which will later appear, are accomplished by the simple and practical construction and arrangement of parts hereinafter described and exhibited in the accompanying drawings, forming part hereof, and in which:

Fig. 1 is an elevational view of a window embodying the invention.

Fig. 2 is a sectional view taken on line 2—2 of Fig. 1.

Fig. 3 is a sectional view taken on line 3—3 of Fig. 1.

Fig. 4 is a perspective view of a member used in the window construction.

Fig. 5 is a perspective view of a member adapted to coact with the member shown in Fig. 4, and

Fig. 6 is a side view of a spring used in the device.

Referring to the drawings, in Fig. 1 there is shown a window sash for a bus or the like, having a glass 1, which has its side edges and upper edge bound in glazing tape 2, and positioned in a channel metal strip 3. The side walls of the channel metal strip 3 are bent back upon themselves to provide spaced walls 5 forming narrow channels in which are mounted strips of felt 6, which project beyond the bottom walls of the channel strip 3.

The portion of the channel strip 3 embracing the upper edge of the glass 1 is not provided with a felt strip; but is covered by a suitable cap 7 in order to provide a finished appearance and prevent the entrance of water.

The felt strips 6 bear against the bottom 8 of a channel member having side walls 9. Mounted upon the bottom wall 8 of the channel member (see Figs. 4 and 6) are a plurality of spaced torsion springs 10 having legs 11 which are fixed to the bottom wall 8 and legs 12 which are slideable thereon, the inward movement of said legs 12 being limited by a stop 13 projecting from the bottom wall 8. The springs engage wall 14 of a substantially channel casting having an outer wall 15 and a short longitudinal partition 16 spaced therefrom, one wall 9 of the last mentioned channel member being positioned in the space between wall 15 and partition 16. The wall 15 being on the outside of the window, is adapted to be covered with a sheet of suitable metal veneer 17 for ornamental purposes if so desired.

It will be noted that the wall 15 extends over the wall 5 of the channel strip 3, and the arrangement above described prevents water from coming in contact with the springs 10 and other parts of the device. It will be seen that in order for water to come into contact with springs 10 it is necessary for the water to pass along the inner surface of wall 15 and then back again between the partition 16 and wall 9 of the channel member having the bottom 8.

The casting has an inner wall 18 to which is attached a suitable guide plate 19 on the inside of the window. The casting 14 is secured to the window casing 20 by means of screws or similar means and a water-tight seal is provided by strips of felt 21.

Springs 10 exert substantially the same force at all times. That is, when they are in the raised position, the force of each spring is approximately ten pounds and when the spring is depressed it has been found that the force is practically the same. By using a spring of this

type, a uniform pressure upon the side edges of the window is assured at all times and it facilitates the raising and lowering of the same, and compensates for any tendency towards binding. Heretofore, when springs of a different construction were used, the force exerted by the spring varied considerably and often caused binding of the window.

The channel strip 3 which preferably consists of one piece, can be readily mounted on the top and side edges of the glass 1 and provides a simpler structure than heretofore has been the case with windows of this type. The felt strips 6 are protected from dampness by the walls 5 and the wall 15, so that they can slide freely at all times over the bottom wall 8 of the channel member.

Punched from the wall 8 are a plurality of tabs 22 which provide openings 23 to receive a latch for holding the window in various raised positions. The latch is operable by a handle 24 mounted upon the bottom rail 25 of the window cash.

From the above description it will be seen that there has been provided a window construction which prevents binding at all times of the window sash during the process of being raised or lowered. Binding is prevented by maintaining a uniform pressure upon the side edges of the window sash at all times, this uniform pressure being assured by the springs 10 which exert the same force regardless of the extent to which they may be depressed.

The channel strip 3 can be manufactured at a very low cost and can be quickly mounted upon the edges of the window glass. The amount of felt necessary is reduced to a minimum by the structure herein described; and the felt is protected from dampness so that it will have no tendency to have a binding effect as has heretofore been the case in windows using other constructions with felt. The moving parts of the window construction are protected from rain and water by providing a tortuous path for the water and thus preventing admission of water to the moving parts and the inside window sill.

The foregoing disclosure is to be regarded as descriptive and illustrative only, and not as restrictive or limitative of the invention, of which, obviously, embodiments may be constructed, including many modifications, without departing from the spirit and scope herein set forth and denoted in the appended claims.

Having thus described my invention, what I claim as new and desire to secure by Letters Patent, is:

1. In a window construction, a window sash, a channel member having a bottom wall engaging said sash, a plurality of torsion springs mounted on the bottom wall of the channel member, 5 each of said springs having a fixed leg and a movable leg and an intermediate coil portion, and a second channel member in which the first channel member is slidably positioned, said channel members opening towards each other, 10 the coiled portions of said springs bearing against the bottom wall of the second channel member and exerting at all times substantially the same force.
2. In a window construction, a window sash, a channel member having a bottom wall engaging said sash, a plurality of torsion springs mounted on the bottom wall of the channel member, each 15 of said springs having a fixed leg and a movable leg and an intermediate coil portion, and a second channel member in which the first channel member is slidably positioned, said channel members opening towards each other, the coiled portions of said springs bearing against the bottom wall of the second channel member and exerting at all times substantially the same force, 20 said second channel member having a partition therein, the first channel member having a side wall positioned in the space between said partition and a wall of said second channel member.
3. In a window construction, a window sash, a channel member having a bottom wall engaging the side edges of said sash, a second channel member having a partition spaced from a side wall thereof, said channel members opening towards each other, the first channel member having a wall thereof slidably positioned in the space 25 between said partitions and the side wall of the second channel member, and resilient means mounted on the bottom of the first channel member and engaging the bottom of the second channel member at all times with substantially the same force.

4. In a window construction, a window sash, a channel member having a bottom wall engaging the side edges of said sash, a second channel member having a partition spaced from a side wall thereof, said channel members opening towards each other, the first channel member having a wall thereof slidably positioned in the space 30 between said partition and the side wall of the second channel member, and resilient means mounted on the bottom of one of the channel members and engaging the bottom of the other channel member at all times with substantially the same force.

SIEGFRIED E. BLESSIN.
